Primary Examiner—A. Hugo Word*Assistant Examiner*—M. Brown[57] **CLAIM**

The ornamental design for a handlebar mountable drink holder, as shown and described.

DESCRIPTION

FIG. 1 is a right side elevation view of a handlebar mountable drink holder in accordance with my invention, the left side thereof being a mirror image;

FIG. 2 is a front view thereof;

FIG. 3 is a rear view thereof;

FIG. 4 is a top view thereof;

FIG. 5 is a bottom view thereof; and,

FIG. 6 is a perspective view thereof, the broken lines are shown for illustrative purposes only and form no part of the claimed design.

FIG. 1

FIG. 4FIG. 5FIG. 2FIG. 3

FIG. 6
